Patented July 15, 1975

235,903

COMBINED PLAYGROUND CLIMBER AND SLIDE OR THE LIKE

Ronald W. Zick, Coldwater, Mich., assignor to
Game Time, Inc.

Filed Feb. 25, 1974, Ser. No. 445,619

Term of patent 14 years

Int. Cl. D21—03

U.S. CL. D34—5 H

FIG. 1

FIG. 2

Des. 235,903

PAGE 2

FIG. 3

FIG. 4

FIG. 1 is a front, elevational view of a combined playground climber and slide or the like in accord with my new design;

FIG. 2 is a rear, elevational view;

FIG. 3 is a side elevational view of my new design as taken from the right of FIG. 1, the opposite side thereof being the mirror image; and

FIG. 4 is a top plan view of my new design.

I claim:

The ornamental design for a combined playground climber and slide or the like, substantially as shown and described.
